DESIGN FOR AN EMBROIDERED LACE OR SIMILAR ARTICLE

George L. Menzer, Union City, N. J.

Application November 12, 1938, Serial No. 81,031

Term of patent 3½ years

To all whom it may concern:

Be it known that I, George L. Menzer, a citizen of the United States, residing in Union City, county of Hudson, State of New Jersey, have invented a new, original, and ornamental Design for an Embroidered Lace or Similar Article, of which the following is a specification, reference being had to the accompanying drawing, forming a part thereof.

The drawing is a plan view of an embroidered lace or similar article, showing my new design.

The embroidered lace is shown on a black surface to bring out the details thereof.

I claim:

The ornamental design for an embroidered lace or similar article, as shown and described.

GEORGE L. MENZER.
